Attorney.

UNITED STATES PATENT OFFICE.

WILLIAM A. OUBRIDGE, OF COVENTRY, ENGLAND.

ROTARY CASTING-MACHINE MOLD.

1,418,826.

Specification of Letters Patent. Patented June 6, 1922.

Application filed July 5, 1921. Serial No. 482,498.

To all whom it may concern:

Be it known that I, WILLIAM ARTHUR OUBRIDGE, a subject of the King of Great Britain and Ireland, residing at Coventry, in the 5 county of Warwick, England, have invented new and useful Improvements in Rotary Casting-Machine Molds, of which the following is a specification.

This invention relates to rotary casting machine molds of the kind in which the mold-parts separate in the direction of their axis, and especially that kind of machine mold in which the metal is pressed when molten into shape by centrifugal force due 10 to the rapid rotation of the mold. Such a machine forms the subject of the specifications of a British Patent, No. 118,304 and of a United States Patent, No. 1,325,039, both granted to William Arthur Oubridge. 15 According to those specifications the separating mold-parts are held together by pressure applied axially to hold a front-plate carried by ball-bearings and a mold proper, carried by a sleeve, in frictional contact each with 20 the other. In other machines of the rotary type the front-plate has hitherto been bolted or hinged to the mold by which alone it was carried.

Where the front-plate and mold are held 25 together by frictional contact and axial pressure only, as in the case above specified, great strain is thrown on the ball-bearings which, moreover, owing to their proximity to the hot mold, it is feared may rapidly 30 wear, fail or otherwise give trouble. Moreover, such bearings are very expensive, especially when applied to large machines. Otherwise this is a satisfactory construction 35 for molds such as specified and for the withdrawal therefrom of the castings which, being necessarily thin, must be removed from the mold immediately they are set, in order to prevent chilling of their surfaces to an extent that would so harden them as 40 to prevent the subsequent use of cutting tools upon them. The method of bolting or hinging the front-plate in place, on the other hand, while it involves no strain on any bearing, yet necessitates opening and closing of 45 the mold by hand, and, owing to the length of time required in this operation, the surface

of the casting is jeopardized by the rapid cooling which continues while it remains in the mold. Another disadvantage attending the hinging of the mold-part, say a door, 55 that it necessitates free room in which the door part may swing, thus depriving the machine of a valuable, otherwise available space, renders it bulky and also tends to restrict the employment of means for mechanically handling the casting.

The object of this invention is to provide a mechanical means for attaching and detaching the parts of molds such as above specified; for example a bayonet joint as 65 has been proposed for the two-part centrifugal mold cases used in making phonograph records, or the interrupted screw threads of a gun breech and block, for allowing quick withdrawal of the castings therefrom as 70 soon as they are set; to embody the advantages possessed by mold-parts held against each other by axial pressure and friction only and also those of mold-parts hitherto bolted or hinged together, while avoiding 75 the disadvantages of both these means of attachment and detachment.

According to this invention a centrifugal metal casting machine molds has its separable parts attached together for the casting 80 operation by means of a device adapted to draw the said parts one toward the other or to force them apart, when they are relatively moved about their common axis, and a mechanically operated gripping means 85 is employed for holding one of said parts stationary while the other part is being moved relatively thereto.

A carriage on the casting machine bed is furnished with a means for holding one 90 mold-part, for example the front-plate, fast when desired, and for supporting it while the casting is being removed from the mold.

In one example of a casting machine mold constructed according to this invention and 95 shown in the accompanying drawings:—

Fig. 1 is a side view partly in vertical axial section thereof, and

Fig. 2 is an end view of the machine shown in Fig. 1.

The parts of the mold are formed by a hollow cylindrical member 1 a mold-piston

2 and a front-plate 3, the cylindrical wall 4 of the member 1, the radial wall 5 of the piston 2 and the radial wall 6 of the front-plate 3 forming the boundaries of the centrifugal mold.

Thus, a cross section of the casting space is shown between the radial walls 5 and 6, the cylindrical wall 4 and the dotted line 7.

The parts 1 and 3 of the mold are attached

- 10 one to the other by a bayonet joint device, the pins 8, 8 of which are mounted on the part 1 and carry anti-friction rollers adapted to engage slots 9 cut in a flange 10 that forms part of the front-plate 3. The said 15 plate 3 is formed with a groove 11 at its periphery within which the circular gripping jaws 12, 12 of levers 13, 13 are adapted to fit. These levers 13, 13 are pivoted at their lower ends 14, 14 to a slide 15 adapted for 20 movement along the machine bed 16 by rack and pinion 17 and 18 respectively. Between the said jaws 12, 12 and the pivots at 14, 14 the former are furnished with nuts 19, 19 for engaging right and left hand screws on a spindle 20 furnished with a hand-wheel 21, so 25 that by rotating this wheel the jaws 12, 12 may be caused to grip the front-plate 3 and hold it immovable.

- The mold 1 is carried by a sleeve 22 furnished with heat dissipating gills 23, and having journals adapted to rotate in bearings 24, 24 on a carriage 25. The mold-piston 2 is mounted on a rod 26 which passes through the sleeve 22 and is furnished with 35 a compressed air piston 27 adapted to work in a cylinder 28 fixed at the end of the machine farthest from the mold-piston 2.

- On the sleeve between the bearing 24, 24 is mounted a strap and brake pulley 29 40 adapted to be driven by a shifting band 30 and also to be braked by a strap brake 31.

- The cylinder 28 is furnished with an admission and exhaust pipe 32 and also with a three way valve (not shown). It is moreover, furnished with a compression spring 33 adapted to return the piston 27 when the compressed air is allowed to escape.

- To operate the machine shown in the drawings for casting a piston ring, the mold-parts 1 and 3 are first caused to engage by turning one relatively to the other when they are in contact and pressed together. Next the screw spindle 20 is turned so as to partly open the jaws 12, 12 of the lever 13 and release the front-plate or mold-part 3. The rotation of the part 1 is then started for example by shifting the band 30 to the fast pulley of the second shaft (not shown). The pin 8 and its roller then enter further into 55 the slot 9, and owing to the inertia of the part 3 or to the braking effect of the jaws 12, 12 they press on the right hand of the said slot 9 and so draw the parts 1 and 3 together; the more tightly as the inertia is 60 greater or the braking effect increases.

The mold is then rotated rapidly and the metal poured into the casting space therein by means of a common pourer spout, the end of which passes through the mold-part or cover 3, as usual. The rotation is continued until the casting is set, then the driving band 30 is shifted to the loose pulley of the second shaft and the band-brake 31 applied and, when the mold-parts 1, 2 and 3 have been arrested, the screw spindle 20 is turned so that the jaws 12, 12 grip the front plate or cover 3 and the mold-part 1 is turned backward to disengage the parts 1 and 3 so that the pin 8 and the roller leave the slot 9. The pinion 18 is then turned by means of the capstan head fast on the pinion shaft, to move the carriage 15, and mold-part 3, now carried thereby, clear of the part 1 so that the casting when ejected may fall out between the mold-parts 1 and 3.

To eject the casting compression air is admitted to the cylinder 28 to force the air piston 27, and consequently the mold-piston 2 to the left-hand so that the casting is slid 80 axially from the mold-part 1. The air is then released from the cylinder 28 and the spring 33 withdraws the pistons 27 and 2 and their common rod 26 until these parts are again in the positions required for the casting operation which may then recommence.

I claim:—

1. In a centrifugal metal-casting machine the combination of a mold having separable mold-parts attached together for the casting operation by means of a device adapted to draw the said mold-parts one toward the other or to force them apart when they are relatively moved about their common axis and a mechanically operated gripping means for holding one of said mold-parts stationary whilst the other mold-part is being moved relatively thereto, substantially as described.

2. In a centrifugal metal casting machine the combination of a mold having separable mold-parts attached together for the casting operation by means of a device adapted to draw the said mold-parts one toward the other or to force them apart when they are relatively moved about their common axis and a mechanically operated gripping device for holding one mold-part and comprising a pair of levers having opposed jaws adapted to grip the said mold-part between them at a part thereof that is concentric to the mold axis and means for forcing the jaws, one toward or one away from the other, substantially as described.

3. In a centrifugal metal casting machine the combination of a mold having separable mold-parts attached together for the casting operation by a bayonet joint device the pins on one part of which engage slots on the other part to draw the said mold parts one toward the other or to force them apart

when they are relatively moved about their common axis, with a mechanically operated gripping device for holding and releasing one mold-part and comprising a pair of levers having opposed jaws adapted to grip the said mold-part between them, pivoted at their ends opposite said jaws and moved apart, or one toward the other by turning a shaft having right and left hand screws each engaging a corresponding nut pivoted to one 10 of the said levers between the ends thereof, substantially as described and for the purposes specified.

WILLIAM A. OUBRIDGE.
